UNITED STATES PATENT OFFICE.

HERBERT S. FAIRCHILD, OF ELLSWORTH, KANSAS.

WATER-FOUNTAIN.

1,035,780.

Specification of Letters Patent. Patented Aug. 13, 1912.

Application filed April 1, 1911. Serial No. 618,292.

To all whom it may concern:

Be it known that I, HERBERT S. FAIRCHILD, a citizen of the United States, residing at Ellsworth, in the county of Ellsworth 5 and State of Kansas, have invented new and useful Improvements in Water-Fountains, of which the following is a specification.

The invention relates to water tanks, and 10 more particularly to the class of drinking fountains.

The primary object of the invention is the provision of an apparatus of this character which is reliable and efficient in use, of comparatively simple and inexpensive construction, and so designed that a substantially uniform water pressure can be obtained at the nozzle or drinking cup thereof, so that the device is especially useful in such places 20 as public buildings, in small towns, passenger coaches, parks, and the like, where drinking cups are dispensed with.

Another object of the invention is the provision of an apparatus of this character 25 in which the tank thereof is of novel character, having a feeding chamber, wherein a uniform level of water is attained, so that water will feed to the nozzle at a constant head, the parts of the apparatus being 30 readily removable, thereby enabling cleaning, repairing, renewal of the parts, and inspection thereof, thus assuring sanitary conditions at all times.

A still further object of the invention is 35 the provision of an apparatus in which the water delivery current is automatically controlled, thus assuring a uniform level of water and a uniform pressure of the same in the nozzle accessible to the public.

With these and other objects in view, the 40 invention consists in the construction, combination and arrangement of parts, as will be hereinafter more fully described, illustrated in the accompanying drawings, and 45 pointed out in the claims hereunto appended.

In the drawings: Figure 1 is a vertical 50 central longitudinal sectional view of an apparatus and the drinking cup nozzle attached, the same being constructed in accordance with the invention. Fig. 2 is a sectional view on the line 2—2 of Fig. 1. Fig. 3 is a sectional view on the line 3—3 of Fig. 1. Fig. 4 is a fragmentary top plan 55 view of the cup-like nozzle. Fig. 5 is a sectional view on the line 5—5 of Fig. 1.

Fig. 6 is an enlarged fragmentary vertical sectional view through the tank and the float chamber therein, showing in detail the connection between the same. Fig. 7 is a top plan view of the valve. Fig. 8 is a side elevation thereof.

Similar reference characters indicate corresponding parts throughout the several views of the drawings.

Referring to the drawings by numerals, 10 designates the main tank or reservoir, which is adapted to contain ice cold water, the same being closed at its top by a removable cover 11, the latter being provided with a central hand knob 12 in the ordinary manner, and its cover is adapted to form an air-tight closure for the tank or reservoir when thereon. The bottom 12 of the tank or reservoir is spaced a suitable distance 70 from its base rim 13, which latter is adapted to rest upon a shelf or other support for holding the tank or reservoir.

Located within the tank or reservoir 10 and rising from the bottom thereof is a feed chamber, comprising a circular or annular vertical wall 14, the latter being of slightly less diameter than the tank or reservoir 10, so as to provide a water space 15 therebetween, the wall 14, at its bottom edge, being outturned to form a ring-like flange 16, the same being adapted to rest upon a resilient gasket 17 superimposed upon a bearing ring 18 mounted upon the bottom 12 of the tank or reservoir 10, bolt members 19 being passed through the bearing ring 18, gasket 17 and ring-like flange 16, thus securing the same together and forming a water-tight joint therebetween.

Formed near the upper edge of the annular wall 14 is an internal annular bearing shoulder 20, upon which rests a detachable or removable cover plate or disk 21, the under face thereof being formed with depending radially extending reinforcing webs or ribs 22, while upon the upper face thereof, at its outer peripheral edge, are formed spaced wedge projections 23, the latter being adapted for locking engagement with in-turned lips 24 formed at intervals throughout the upper edge of the annular wall 14, although on slight turning movement of the plate or disk 21, the same may be detached or removed when desired. Interposed between the shoulder 20 and the peripheral edge of the plate or disk 21 is a resilient gasket 25, which latter serves to form a

fluid-tight joint between the wall 14 and the disk 21 of the feeding chamber.

Formed centrally on the bottom 12 of the tank or reservoir 10 is a depending cup-like trap 26, the same having communication with the feeding chamber through the medium of inlet ports 27 formed in the bottom 12 of the tank or reservoir. Passed through the trap 26, upwardly within the feeding chamber centrally thereof, is a delivery tube 28, the latter being also designed as a guide for a hollow float body 29 arranged within the feeding chamber, the float body 29 being preferably circular in diameter, and is formed with a central guide tube 30, the latter surrounding the delivery tube 28 and being slidably engaged therewith, whereby the float body 29, when rising and falling within the feeding chamber, will be guided in its movements therein.

Closing the upper end of the guide tube 30 of the float body 29 is a valve rest cap 31, the same being detachably threaded in the guide tube 30, and is formed in its upper face with a central indentation 32, receiving a correspondingly shaped projection 33 formed centrally on the bottom of the disk-like valve 34, the latter being adapted to rest upon said cap 31 and to rise and fall with the float body 29. Formed centrally in the plate or disk 21 is an inlet port 35, the latter being surrounded by a valve seat 36 with which contacts the valve 34 on the float body 29, rising within the feeding chamber in the tank or reservoir 10. When the float body 29 lowers within the feeding chamber, the valve 34 recedes from the valve seat 36, thereby opening the port 35 in the plate 21, so that water from the tank or reservoir 10 will enter the feeding chamber.

Rising from the valve 34 are crossing guide wings 37 which engage in the port 35, so as to hold the valve 34 centered and to enable the proper seating thereof on the valve seat 36 when the float rises within the feeding chamber in the tank or reservoir.

Rising in the space 15 between the tank or reservoir 10 and the feeding chamber is an air outlet tube 38, the inner end of which passes into and communicates with the interior of the feeding chamber, while the outer end of this tube 38 passes through the bottom 12 of the tank or reservoir 10. Thus, the air present above the water level 55 within the feeding chamber will be emitted therefrom and exteriorly of the tank or reservoir. Mounted on the outer end of the outlet tube or pipe 38 is an elbow 39, to which is connected a horizontal discharge 60 tube or pipe 40, the latter being also passed through the base rim 13 of the tank or reservoir 10 to the exterior of the latter.

On the outer free end of the discharge tube or pipe 40 is mounted a cup-shaped drinking nozzle 41, in the bottom of which

is formed a circular-shaped cavity 42, the same being in alignment with the discharge tube or pipe 40, and is divided into inner and outer cells 43 and 44, respectively, by means of a perforated valve seat 45, the perforation in the seat 45 being normally closed by means of a resilient valve 46 fixed on the inner end of a push rod or plunger 47 passed centrally through the perforation in the valve seat and the cell 44, and also through a screw cap 48 closing the outer end of the cavity in the bottom of the nozzle. This cap 48 is provided with a packing gland 49, surrounding the plunger 47, thus preventing leakage of water from the cell 44 exteriorly of the cup about the said plunger 47. This plunger 47, at its outer end, carries a push button 50, so that on pressing inwardly upon the latter, the valve 46 may be unseated, thereby establishing communication between the cells 43 and 44, so that water from the discharge pipe 40 may enter the cell 44, and thence enter the nozzle, in a manner as hereinafter more fully described.

Detachably threaded centrally in the bottom of the cup-like nozzle 41 is a vertical nipple 51, the latter leading from the cell 44 into the cup-like nozzle, so that water from the discharge pipe 40 may enter the said nozzle for the filling thereof, when the valve 46 has been unseated, as hereinbefore described. Also formed in the bottom of the cup-like nozzle 41, spaced from and concentrically about the cavity therein, is a downwardly arched drain passage 52, the same opening into the nozzle 41 at opposite sides of the nipple 51, and in communication with this passage 52 and extending outwardly from the bottom of the nozzle 41 is a drain pipe 53, whereby the water contained within the nozzle 41 may be drained therefrom.

The delivery pipe 30 is formed with an inlet port 54, establishing communication between it and the trap 26, so that water in the latter will freely flow into the delivery pipe 30, thence through the discharge pipe 40, and from the same into the drinking nozzle, as hereinbefore explained. It is of course to be understood that ice is placed upon the plate 21 within the tank or reservoir 10 for the cooling of the water held therein prior to its delivery into the feeding chamber within said tank or reservoir, the delivery of the water being controlled by the valve 34, which is also controlled automatically by the rise and fall of the float body 29 in the feeding chamber.

When the valve 46 in the cup-like nozzle 41 is opened, the water flows from the feeding chamber within the tank or reservoir 10 to the said nozzle, and as the water lowers in the feeding chamber, the float body 29 drops and causes the valve 34 to open, so that water from the tank or reservoir will enter the said feeding chamber through the

port 35, thereby immediately replenishing the feeding chamber, and when the level of the water therein is restored, the float body 29 will cause the valve 34 to close. Since 5 the feeding chamber in the tank or reservoir 10 is surrounded by ice cold water, it is obvious that the water in said chamber will 15 always be cool for drinking. It is clearly obvious that the apparatus may be readily 20 cleaned for sanitary purposes, and is also capable of being inspected, repaired, or the renewal of the parts can be readily made.

From the foregoing description, taken in connection with the accompanying drawings, 15 the advantages of construction and method of operation will be readily apparent to those skilled in the art to which the invention relates, and while the principle of operation of the invention is described in detail, together with the apparatus which is now considered to be the best embodiment thereof, it is to be understood, however, that the apparatus shown is merely 25 illustrative, and that such changes, variations and modifications may be made, when desired, as come properly within the scope of the appended claims.

What is claimed is:

1. In a drinking fount, the combination 30 with a tank, of a flange formed interiorly of the said tank, a feeding chamber arranged within the tank and having an external flange superposed above the internal flange on the tank, a packing ring interposed between the said flanges, bolt members engaged in the flanges and the packing ring for fastening the feeding chamber interiorly of the tank, a top plate on the feeding chamber and having a central opening, a pipe 35 passed through the bottom of the feeding chamber in alinement with the opening in its top and having its upper end terminating short of the said top, a float within said feeding chamber and loosely surrounding 40 the pipe, the said pipe being provided with openings communicating with the feeding chamber in a plane below the bottom there-

of, a rest cap mounted centrally on the float and a valve superimposed on the cap and adapted to close the opening in the top 50 of the chamber on the rise of the float.

2. In a drinking fount, the combination with a tank, of a flange formed interiorly of the said tank, a feeding chamber arranged within the tank and having an external flange superposed above the internal flange on the tank, a packing ring interposed between the said flanges, bolt members engaged in the flanges and the packing ring for fastening the feeding chamber interiorly of the tank a top plate on the feeding chamber and having a central opening, a pipe passed through the bottom of the feeding chamber in alinement with the opening in its top and having its upper end terminating short of the said top, a float within said feeding chamber and loosely surrounding the pipe, the said pipe being provided with openings communicating with the feeding chamber in a plane below the bottom thereof, a rest cap mounted centrally on the float, a valve superimposed on the cap and adapted to close the opening in the top of the chamber on the rise of the float, and a drinking cup connected with said 75 pipe.

3. A drinking fount, comprising a tank having an inturned annular flange near its base, a cylinder arranged interiorly of the tank and having a flange adapted to rest upon the flange on the tank, a packing interposed between said flanges, means fastening the flanges together, an outlet conduit leading from the cylinder, a float arranged within the cylinder, a centrally perforated top on the cylinder, and means carried by the float and adapted to close the perforation in the top on the rise of said float.

In testimony whereof I affix my signature in presence of two witnesses.

HERBERT S. FAIRCHILD.
